UNITED STATES PATENT OFFICE.

JAMES H. LUX, OF THOMPSON FALLS, MONTANA.

ELECTRIC-CIRCUIT BREAKER.

1,369,035.

Specification of Letters Patent. Patented Feb. 22, 1921.

Application filed March 3, 1919. Serial No. 280,346.

To all whom it may concern:

Be it known that I, JAMES H. LUX, a citizen of the United States, residing at Thompson Falls, in the county of Sanders, State of Montana, have invented certain new and useful Improvements in Electric-Circuit Breakers; and I do hereby declare the following to be a full, clear, and exact description of the invention, such as will enable others skilled in the art to which it appertains to make and use the same.

The invention relates to an electric circuit breaker and more particularly to the class of mechanically operated switch opening and closing mechanism.

The primary object of the invention is, the provision of mechanism of this character, wherein several or any number of knife switches for controlling electric circuits can be automatically opened and closed for the controlling of the electric current or currents to and from a sign or other electrically operated device, the mechanism being of novel form to assure the positive opening and closing of the switches.

Another object of the invention is, the provision of mechanism of this character, wherein the electric switches are mounted in a novel manner and automatically controlled for the opening and closing thereof during the working of said mechanism.

A further object of the invention is, the provision of mechanism of this character, which is simple in construction, operative for the automatic opening and closing of electric switches, thoroughly reliable and efficient in operation, positive in action and inexpensive to manufacture and install.

With these and other objects in view, the invention consists in the features of construction, combination and arrangement of parts as will be hereinafter fully described, illustrated in the accompanying drawing and pointed out in the claims hereunto appended.

In the accompanying drawing:

Figure 1 is an elevation of the electric circuit breaker mechanism constructed in accordance with the invention.

Fig. 2 is a front elevation thereof.
Fig. 3 is a vertical sectional view.

Fig. 4 is a sectional view on the line 4—4 of Fig. 1.

Fig. 5 is a sectional view on the line 5—5 of Fig. 1.

Fig. 6 is a perspective view on the cam wheel of the mechanism.

Similar reference characters indicate corresponding parts throughout the several views of the drawing.

Referring to the drawings in detail, A, designates generally the base of the circuit breaker mechanism, from which rises spaced vertical uprights 10 and 11 respectively, the upright 10 being formed with an upper fork end 12, the arms of which are provided with vertical slots 13 in which is movably supported a bearing block 14 carrying a horizontal spindle 15. Acting upon this block 14 are adjusting screws 16 which are mounted in a stationary bridge 17 secured in the closed ends of the slots 13, the screws 16 being fitted with binding nuts 18, through the medium of which the bearing block can be raised or lowered in the forked upper end 12 of the upright 10 and held in adjusted position by a set screw 16' for a purpose presently described.

The upright 11 is of considerably less height than the upright 10, and journaled transversely in these uprights is a horizontal shaft 19, on which is mounted a driving belt wheel 20 adapted to have trained thereover an endless belt 20' which is driven from a motor 21' preferably of the electric type of any suitable construction adapted to be started and stopped in the usual manner by a switch. Also carried by the shaft 19 is a belt pulley 21, over which is trained an endless belt 22, the same being also trained over the peripherally grooved pulley rim 23 of a cam carrying wheel 24 which is fixed to or journaled on the spindle 15, to rotate the wheel 24 for a purpose presently described.

Mounted upon the upright 11 for vertical adjustment, is an inverted substantially L-shaped bracket 25, while mounted upon the bearing block 14 and overhanging the bracket 25 is a hanger 26, and connected to said bracket and hanger forwardly of and concentrically relative to the cam carrying

wheel 24, is a ring 27 which may be tubular or a plane band, carrying thereon one or a plurality of electric knife switches 28 for opening and closing one or more electric circuits of electric flash signs or the like; it being understood that each switch is connected to the source of energy and a sign or part thereof or other suitable device to be illuminated or operated. The conductor 10 wires may be suitably trained through the ring 27 and are connected with the posts 30 and 31 respectively, of said switches, the handle end 29 of the knife of the switch 28 being extended forwardly toward the outer 15 face of the cam carrying wheel 24 which has arranged thereon diametrically opposed or otherwise suitably spaced reversely set and acting cam protuberances 32 and 33 respectively, adapted to successively engage the 20 handle end of the switch knife or blade for the opening and closing thereof automatically on the rotation of the cam carrying wheel 24, and thereby make and break the circuit in the opening and closing movement 25 of the switch, as will be clearly obvious.

The adjustment of the bearing block 14 and the wheel 24 radially of the ring 27 can be had with accuracy for the proper positioning of the cams 32 and 33 respectively, 30 with respect to the switches to assure positiveness in the operation of the circuit making and breaking mechanism. As shown, the cams 32 and 33 are located at different distances from the axis of the wheel 24, the cam 32 being located at the peripheral edge 35 and serving to move the switch handle 29 inwardly on its pivot, while the cam 33 is spaced inwardly from the peripheral edge of the wheel to move the switch handle outwardly. To facilitate this operation, the cam 32 is directed outwardly slightly while the cam 33 is similarly directed inwardly so as to strike and deflect the handle in each instance, as they pass by the handle, irrespective of the number of switches employed 40 and the number of cams employed, and the relation of the latter relative to each other circumferentially.

Clamping screws 25' are engaged through 50 vertical slots in the vertical portion of the bracket 25 and with the upright or standard 11, so that the bracket can be adjusted vertically and held in adjusted position on the upright. Also, through the vertical adjustment of the block 14 the wheel 24 may be shifted toward and away from the pulley 21 so as to properly adjust the belt 22.

It is also to be understood that in lieu of the knife or single throw switches 28, any 60 other desired or approved form of switch may be employed, such as a "goose neck" or double throw switch 28' so that upon actuation of the knife or blade thereof, the blade will move out of contact at one side and 65 into contact at the other side to open one

circuit and close the other, as is the purpose for which such switches are intended. Any number of arms may be provided on the portion of the hanger 26 where anchored to the bearing block 14 for supporting the 70 ring 27, and further any other changes may be made in the construction and relation of the parts as come within the scope of the device as claimed.

It will be seen that the mechanism is useful for controlling electric signs or other 75 electrically actuated devices and will successfully serve to open and close electric circuits, it being obvious that any number of 80 circuits may be controlled, as a plurality of 85 switches can be mounted upon the ring 27 to arrive at this end and thereby meet differing conditions in the use of the mechanism. It is also obvious that by reason of the band 27 having a continuous peripheral 90 series of perforations the knife switches may be set as desired within the band so that the timing relation of the switches and the throw means may be correspondingly varied.

What is claimed is:

1. The combination with an electric knife switch, of a ring having the switch mounted thereon, a rotatable cam carrier having cams operable upon the knife switch to successively open and close the same. 95

2. The combination with an electric knife switch, of a ring having the switch mounted thereon, a bracket connected with said ring, a rotatable carrier having cams operable upon the knife switch to successively open and close it, a standard by which the cam carrier is supported and a second standard with which said bracket is adjustably connected to position the ring in axial alignment with the carrier. 105

3. The combination with an electric knife switch, of a ring having the switch mounted thereon, a support, a cam carrier rotatably carried by the support and having cams operable upon the knife switch to successively open and close them, a second support, a bracket carried by the second support and upon which the ring is mounted, the bracket being adjustable on the support to axially align the ring with the cam carrier, and means carried by said supports and connected with the cam carrier for actuating it. 110

4. A circuit breaker including a ring having openings formed therein, a knife switch secured in a selected opening of the ring, a revoluble wheel, and cams on the wheel, said cams having oppositely directed cam faces movable into engagement with the knife switch as the wheel revolves to alternately open and close the switch. 120

5. A circuit breaker including a frame, a block adjustable in the frame, a spindle mounted in the block, a wheel journaled upon the spindle, a bracket adjustable upon 130

the frame, a switch support carried by the bracket and adjustable therewith into and out of axial alinement with the wheel, a hanger connected with the block and with 5 the switch support, cams on the wheel and a knife switch mounted upon the switch support in position for engagement by the cams when the wheel is revolved, for operation of the switch, and driving means for the 10 wheel.

6. In a circuit breaker, a vertically disposed ring having openings formed therein, a series of spaced switches secured in selected openings of the ring, a vertically disposed disk, cams carried thereby for alternately opening and closing the switches, a support having spaced standards, the disk being rotatably connected with one standard, a bracket adjustably connecting the 15 ring with the second standard for support- 20

ing the ring in axial alinement with the disk, and means for rotating the ring and disk one relative to the other.

7. The combination with a series of throw switches located in a common circle and 25 adapted for independent connection in circuit with a source of energy and a sign to be illuminated; of means to successively turn said switches to alternately open and close the same to correspondingly effect the 30 circuits thereof and means to adjust the timing relation of said switches and throw means.

In testimony whereof, I affix my signature, in the presence of two witnesses.

JAMES H. LUX.
